UNITED STATES PATENT OFFICE.

GEORGE SEIBT, OF NEW YORK, N. Y.

MEANS FOR INCREASING THE SPEED OF TRANSMISSION OF SIGNALS OVER TELEGRAPH AND CABLE LINES.

1,063,396.

Specification of Letters Patent.

Patented June 3, 1913.

Application filed October 12, 1909. Serial No. 522,225.

To all whom it may concern:

Be it known that I, GEORGE SEIBT, a subject of the Emperor of Germany, residing in the city, county, and State of New York, have made a certain new and useful Invention in Means for Increasing the Speed of Transmission of Signals Over Telegraph and Cable Lines, of which the following is a specification.

- 10 This invention relates to means for increasing the speed of transmission of messages or signals over deep sea, long distance, or other cables or conductors, telegraphically or otherwise.
- 15 The invention consists substantially in the construction and arrangement hereinafter set forth, as illustrated in the accompanying drawings and finally pointed out in the appended claims.
- 20 It is a well-known fact that the speed of transmission of telegraphic messages or signals over long cables or very long land lines depends more upon the quality of the cable or conductor itself than upon the receiving or transmitting apparatus or instrument employed. In the practical operation of cable and long land telegraphic lines it is a common practice to consider as a measuring unit for the retardation of signals or messages in transmission, the product of the capacity and resistance of the conductor. As both quantities are proportional to the length of the conductor, the speed of transmission decreases according to the square of the length of the conductor. Consequently, a limit is reached in the length of conductors beyond which it is difficult to maintain a profitable operation of the line for the transmission of messages or signals. By reason of this difficulty, it is common practice to employ relay stations at some convenient point along the cable or line in which the messages or signals transmitted are received from one or the other transmitting stations at the ends of the cable or line, and then such messages or signals are resent from the relay station. It is also the prac-

tice in some instances to employ automatic relays for receiving at such intermediate or relay station the transmitted messages or signals and automatically to repeat or re-lay the same on toward the other end of the line. The use of a relay station, whether automatic or otherwise, is objectionable for the reason that it involves additional operating cost and expense. Moreover, it is evident that such relays cannot always be conveniently used, as, for instance, in deep sea cables, available relay stations are not obtainable. Moreover, in receiving and re-laying messages, the danger of error in the transmitted message is multiplied.

It is among the special purposes of the present invention to provide means whereby the speed of transmission of messages may be greatly increased without the necessity of establishing or employing automatic or other relay stations or apparatus, without the necessity of employing extra labor or extra operating expense, and to avoid the danger, annoyance and objection of errors in transmission due to the double reception and transmission of the messages.

In arriving at the discovery embodying the present invention, I have been influenced by the following theoretical considerations: The differential equations for calculating the potential and current in telegraphic conductors, the self-induction of which may be neglected, but the leakage from which must not be neglected, are as follows:

$$(1) \frac{\partial^2 V}{\partial x^2} = CW \frac{\partial V}{\partial t} + gWV$$

$$(2) \frac{\partial^2 I}{\partial x^2} = CW \frac{\partial I}{\partial t} + gWI$$

85

wherein C is capacity, W is resistance, g the leakage per unit of length, V is potential, I is current and x the location of the point in the length of the cable at which the calculation is to be made. If the conductor at the receiving end is connected to ground and

at the other end is connected to one pole of a battery, the second pole of the battery being connected to ground, the solution for equation 1 is the following, by integration:

$$5 \quad Vxt = V^1 + e^{-\frac{gt}{c}} \sum_{n=1}^{\infty} Ae^{-\frac{n^2\pi^2t}{l^2WC}} \sin. \frac{n\pi x}{l}$$

in which n runs through all non-fractional members. If, however, the connection of the conductor with the battery is broken, as, for instance, by raising the key, the solution from the moment of opening the circuit of the conductor is as follows:

$$15 \quad Vxt = e^{-\frac{gt}{c}} \sum_{m=\frac{1}{2}}^{\infty} Be^{-\frac{m^2\pi^2t}{l^2WC}} \cos. \frac{m\pi x}{l}$$

wherein m runs through the series, $1/2, 3/2, 5/2$, etc. For the intensity of the current we have similar solutions and it is especially remarked that the damping coefficients are the same. From an examination of the solutions of equation 1 and equation 2, as above given, it will be seen that the higher members of the series indicate a considerably stronger damping than the first member of such solutions. Thus, for instance, the second member in the solution of equation 1, indicates a damping four-fold that of the first member, and the second member in the solution of equation 2, indicates a damping of nine-fold the first member thereof. Therefore, it will be sufficient for the theoretical computation to consider only the first members of the equations, as all of the subsequent members thereof may be neglected. The damping coefficients of the solutions of the equations, that is, the factors which determine the damping rate, may be expressed as follows:

$$\alpha_1 = \frac{g}{c} + \frac{\pi^2}{l^2WC}$$

45 and

$$\alpha_2 = \frac{g}{c} + \frac{\pi^2}{4l^2WC}$$

During the transmission of messages or signals over the conductor, said conductor, at the transmitting end, is being repeatedly opened and closed or grounded through the battery; that is, during the operation of transmission of the message, the manipulation of the key first grounds the conductor through the battery and then opens the conductor, and this operation is successively repeated, while, at the receiving end, the receiving apparatus offers a resistance to the flow of current through the conductor, which resistance slightly delays the outlet of the current to the ground at the receiving end of the line and, consequently, in our theoretical calculations, we will have to take into consideration a damping effect of medium

strength and which can be estimated to be represented by the following equation:

$$(3) \quad \alpha = \frac{g}{c} + \frac{\pi^2}{2l^2WC}$$

where l is the length of the conductor. From a consideration of these theoretical calculations it will be seen that an increased leakage is desirable in order to attain the best theoretical results. It is not desirable, however, to decrease the resistance of the insulating material in order to secure the desired increase of leakage, as to do so would result in increasing the danger of short circuits. With deep sea cables in which gutta percha is used as the insulating material, the first member of the above stated equations and their solutions may be neglected as compared with the second members of said solutions. In other words, it is desirable in the use of deep sea cables to increase the leakage without decreasing the insulation in order to avoid the danger of short circuits. Therefore, in accordance with the principles of my present invention, I propose to attain these desirable results, and, as one form of means for accomplishing the desired object, I propose to employ what may be termed an artificial leakage, as, for instance, by inserting resistances between the conductor and the ground or return circuit, and this forms an important part of my present invention. I shall designate this characteristic of my invention as an artificial leakage, but I desire it to be understood that this term is used in a broad and generic sense, and that one specific form or embodiment thereof is the insertion of a suitable resistance in the long distance line or cable or a series of such resistances at various points throughout the length of the cable or line.

In the drawing I have indicated various arrangements for carrying my invention into practical operation, as illustrative of the method set forth.

Figure 1 designates diagrammatically a long distance line or cable for the transmission of messages or signals, and showing at a point intermediate the length of the cable the application of an artificial leakage embodying the principles of my invention. Fig. 2 is a similar view showing the application of a series of artificial resistances connected to the cable or line at uniform distances apart. Fig. 3 is a similar view showing the application of artificial leakages to the cable at various points throughout its length, the distance apart of the artificial leakages increasing from about the mid-length of the cable or line toward the ends thereof. Fig. 4 is an enlarged broken view in section of a cable showing the application of an artificial leakage embodying the principles of my invention. Fig. 5 is a view similar to Fig. 4, showing a modified con-

struction and connection of the artificial leakage.

In Fig. 1 the cable A is grounded at one end as B, which may be considered, for example, as the receiving end of the cable, the grounding being effected in the ordinary manner through the receiving apparatus. A source of current C is placed in the circuit of the cable at its other end which, for example, may be considered the transmitting end, D representing the key, the source of current C being grounded as at E. The artificial leakage is indicated at G and may be represented diagrammatically as a resistance connected to the cable at, say, for instance, a point midway its length and grounded or connected to the return as at H. If this artificial leakage G is small in comparison to the resistance of the cable or conductor A, the insertion of this artificial leakage or resistance G at a point at the mid-length of the conductor will have the same effect upon the damping of the conductor as if the length of the conductor were decreased by one-half. By an examination of the equation last above given, which I have designated as equation 3, it will be seen that, with the length of the cable reduced by one-half, the damping is increased four-fold. If the resistance or artificial leakage is increased the damping is naturally increased correspondingly. In case the diverting resistance or artificial leakage is distributed throughout the length of the cable at not too lengthy intervals apart and the resistances of the diverting leakages are large in comparison to the resistances of the sections of the cable between them, the cable should then act similarly to a defective insulation and consequently the equation 3 may be used for calculating the damping effect.

In Fig. 2 I have shown a plurality of diverting resistances or artificial leakages G connected to a cable A at equal distances apart throughout the length of the cable. In this arrangement, however, it is usual to employ equal diverting resistances or artificial leakages. I do not desire, however, to be limited or restricted in this respect, since the same results may be attained by employing diverting resistances or artificial leakages of different degrees but spaced at unequal distances apart throughout the length of the cable or line and preferably the diverting resistances are placed closer together as the mid-length of the cable or conductor is approached. A specific example with figures will show to what a high degree the damping effect can be increased by employing the diverting resistances or artificial leakages. Suppose the length of the cable is 1,000 sea miles; and suppose the capacity of the conductor per sea mile is 0.32 micro-farad, and the resistance of the conductor 10 ohms. With an efficient insu-

lation for the conductor it will be found, according to equation 3, above given, that

$$c=1.54$$

If, say, ten artificial leakages or diverting resistances having a resistance of 10,000 ohms each, are inserted into the cable at equal distances apart so that

$$g=10^{-6}$$

then

75

$$\frac{g}{c}=3.13$$

1. An aeroplane including a gliding structure and the entire damping is, as will be seen, thereby increased to 4.67; that is, the damping is increased three-fold.

As above indicated, it is preferable to insert the diverting resistances at irregular distances apart, such distances apart decreasing toward the mid-length of the cable. The reason for this arrangement lies in the fact that the dissipation of the current at the ends of the cable where the conductor is grounded is large anyway, and therefore there is less need for the diverting resistance than at the mid-length of the cable where there is no natural grounding. The same result may be obtained by equally spacing the diverting resistances or artificial leakages, as indicated in Fig. 2, but varying the amounts of such diverting resistances. A merely cursory consideration of the foregoing might lead to the view that with any considerable increase in the damping of the cable the current for signaling or message-transmitting purposes would be reduced and the inertia of the receiving apparatus would assert itself and not permit of any increase in the speed of transmission. According to experiments which I have made, I have found that the ordinary siphon recorders, such as are commonly employed in cable telegraph offices to receive the transmitted messages, have damping coefficients at 15 to 20, so that the mechanical inertia of such devices can be practically neglected in comparison with the electrical inertia of the cable.

One consequence of the insertion of the diverting resistance or artificial leakage which at first glance would seem to make its use a matter of questionable value, may be here pointed out. It would seem that by the use of such artificial leakages or diverting resistances considerable loss of current and strength is entailed, so that the current arriving at the receiving end of the cable is considerably weakened. If, however, the artificial leakages or diverting resistances are inserted in the cable and distributed in short intervals, the departing current for any signal, that is, departing from the transmitting end, to the arriving current, that is, the current at the receiving end, will

95

100

105

110

115

120

125

130

be equal, after the full load of the cable has been attained, to

$$\frac{I_a}{I_e} = \frac{2}{e^{ml} - te^{ml}}$$

5 when

$$m = \sqrt{Wg}$$

Applying this last given equation to the specific example above noted, we find that

10

$$\frac{I_a}{I_e} = 11.8$$

With the three-fold damping of the cable the tendency of the current is to approach its maximum very quickly, that is, the current, after it has reached the stage where it is governed by the ohmic law or its maximum value, has a tendency to try to quickly 15 adjust itself, and in practical operation the time within which this maximum is reached is very short, the rate of flow of the current through the receiving apparatus with the artificial leakage being considerably more 20 favorable to the attainment of the maximum flow of the current than without such artificial leakage, as clearly indicated by the examples above given. It may, however, happen that the siphon recorders or other 25 receiving apparatus commonly employed 30 may lose their usefulness in case of very strong artificial leakage or diverting-resistance and very long conductors because the deflections of the receiving apparatus will 35 then become too insignificant on account of weakness of the current impulses received. In such case, more sensitive receiving apparatus should be used, such, for instance, as the optical printer set forth in my pending 40 application Serial No. 487557 filed April 2, 1909, in which the deflections of a wire galvanometer are microscopically enlarged and photographically registered upon a strip of sensitive paper. Obviously, other 45 forms of sensitive receiving apparatus or devices might be used. I do not desire, therefore, in the broadest scope of my invention as defined in the claims, to be limited or restricted in respect to the particular structure 50 or arrangement of the recording apparatus employed. I have found, however, the optical printer above mentioned most efficient, and comparative tests with an optical printer as embodied in my said application, 55 employing a gold thread of 0.0035 millimeters cross-section and 10 centimeters length arranged in a magnetic field of 1,000 lines of force per square centimeter and a microscope of two-hundredfold magnifying 60 power and an ordinary siphon recorder such as is employed for commercial cable telegraphy, shows the sensibility of the optical printer to be sixty times higher than that of the siphon recorder with the tension of 65 the threads employed in the apparatus so

regulated that the damping coefficients of the instrument were in each case 25. With the optical printer, however, the sensitiveness can be still further increased by increasing the strength of the magnetic field in 70 which the gold thread operates and consequently such apparatus answers to a very high degree the purpose and requirements to be met by a receiving apparatus in commercial cable use with strong artificial leakage 75 or diverting resistance. In other words, any loss of current strength due to the use of the diverting resistance may be more than compensated by increasing the sensitiveness of the receiving apparatus or by employing 80 apparatus of increased sensitiveness. Consequently, any desired type of construction or arrangement of receiving apparatus may be employed, so long as it possesses the required sensibility and self-damping, and 85 still attain the benefits and advantages of the increased rate of transmission contemplated by the practice of my invention.

With reference to the location of the diverting resistances in accordance with my invention, it may be pointed out that with deep sea cables having stations located in the ocean, such resistances may be inserted at such stations. In many cases the insertion at one point only of a diverting resistance or artificial leakage is sufficient to greatly improve and simplify the service, and consequently, by the use of the method of my invention, the relay apparatus at such island station, for instance, as in the case of 100 the trans-Atlantic cable station on the Azores, may be dispensed with by merely inserting at that point the desired or required diverting resistance, thereby avoiding the necessity for maintaining such relay station 105 and its operation of receiving and retransmitting the received messages. Of course the insertion of the diverting resistance in long distance conductors over land does not offer these difficulties, since they may be inserted conveniently at any desired point. With cables which do not touch the land at all or at insufficient points, it is necessary to insert the diverting resistance into the interior of the cable itself. In such case the 110 diverting resistance may be applied to the cable in such manner as not to enlarge the cross-sectional area of the cable itself or at least to a very small extent only. The resistance may be easily inserted in the 115 proximity of the core of the cable or may be placed upon the core.

In Figs. 4 and 5 I have shown methods of applying the diverting resistance to the cable.

Referring particularly to Fig. 4, reference sign 6 designates the core of the cable, 7 its insulation and 8 the inclosing armor. At a convenient point the core of the cable 120 is reduced in thickness or cross-sectional 125 area.

At a convenient point the core of the cable is reduced in thickness or cross-sectional 130 area.

area, as indicated at 9. Upon this reduced portion of the core coils indicated at 10 may be placed. A convenient arrangement is to employ spools of insulating material such for 5 instance as micanite and upon each spool a coil of suitable resistance material such, for instance, as constantan wire, is wound, so that the diameter of the coil wound upon the spool will be approximately the same as the 10 diameter of the unreduced portion of the cable core. I have found that a serviceable construction may be formed of the following proportions: Suppose the thickness of the core of the cable conductor is 5 millimeters and it is reduced at the desired point to about, say, 3 millimeters. A number of the micanite spools of say 0.25 millimeters of 15 wall thickness are then strung upon the reduced portion of the cable core and then 20 constantan wire is wound upon the spools, such wire being attached at one end to the cable core and wound in series upon the spools until the thickness at the point of reduced portion of the cable is again 5 millimeters. If the constantan wire is of 0.05 25 millimeters thickness the total length of the spools employed to attain the resistance of 10,000 ohms will be about 3.5 centimeters. As above indicated, one end of the resistance 30 wire is connected to the core of the cable. The other should be led through the insulation surrounding the core of the cable and attached to the armor. It is advisable to lead the end of the resistance wire through 35 the insulation at an angle as indicated at 12, Fig. 4, thereby avoiding the danger of injuring the insulation. If desired, and in order to increase the mechanical strength of the core at a weakened point of the cable, the 40 copper wires of the core may be replaced by steel wires soldered outside of the copper coil. Of course it will be obvious that where a return wire is employed the resistance should be connected to such return wire instead of being connected to the ground. 45 In Fig. 5 I have shown another form of connection of the resistance which might well answer the purpose. In this arrangement the cable A is led through an iron box 50 13, a portion 14 of the cable core being exposed within said box. A diverting resistance 15 of the desired strength is then connected at one end to the exposed portion 14 of the core and at the other end to the iron 55 box or casing 13. The interior of the iron box or casing is then filled with a suitable insulating compound indicated at 16. In this arrangement it is important to efficiently solder or otherwise secure the ends of the casing upon the cable so as to hermetically seal the ends of the casing. 60

In order to calculate the resistance to be inserted in accordance with the principles of my invention, and in order to determine accurately the proper spacing apart of the resistance where a plurality are employed for any given case, it may be difficult to make the calculations upon the cables themselves as they may be in service and inaccessible. I therefore propose to make the desired calculations upon an artificial cable, that is, a cable loaded to approximately the capacity, length and resistance of the particular cable to be equipped, thereby enabling me to ascertain the correct resistance to be employed 70 for that particular cable and the correct distances apart to place the resistances. 75

Having now set forth the object and nature of my invention and a form of means for carrying the same into practical operation, what I claim as new and useful and of my own invention, and desire to secure by Letters-Patent is.

1. As a means for increasing the speed of transmission of telegraphic signals over a 85 conductor, artificial leakages connected to the conductor at points in the length thereof of increasing distances apart from the midpoint of the length of such conductor toward the ends thereof. 90

2. In a means for increasing the speed of transmission of telegraphic signals over a conductor, the combination with the conductor having a portion of its core reduced in diameter and a resistance coil connected to 95 the reduced portion of the conductor core and to ground or return.

3. In a means for increasing the speed of transmission of telegraphic signals over a conductor, the combination with a conductor 100 having a core reduced in size for a portion of its length, and insulating spools carrying resistance coils connected in series, one end of the resistance coils being connected to the reduced portion of the cable core, and the 105 other end connected to ground or return.

In testimony whereof I have hereunto set my hand in the presence of the subscribing witnesses, on this 11th day of October A. D., 1909.

GEORGE SEIBT.
